ELECTRIC CIRCUIT AND PLUG CONNECTION

Gwilym Stanley Braun, Strasburg, Ohio, assignor to Knapp-Monarch Company, St. Louis, Mo., a corporation of Missouri

Application April 3, 1939, Serial No. 265,657

4 Claims. (Cl. 219—20)

An object of my invention is to provide an electric circuit such as the heating element of an electric appliance and novel plug connections made with the heating element so as to secure either parallel or series operation of the two halves of the heating element.

Another object is to provide means to adapt a heating element or the like for either 110 volt or 220 volt operation by a simple arrangement of two pairs of prongs, one of which is of ordinary construction and the other including one prong of compound character, making it possible to use a standard cord plug therewith and yet secure different circuit connections with the heating element than when the ordinary terminal prongs are associated with the cord plug.

A further object is to provide a structure of this character which is also adaptable for securing two different heats by use of the two pairs of prongs associated with the heating element.

More particularly it is my object to provide terminal prongs which may be associated with a standard cord plug and one of the prongs being formed of two half prongs insulated relative to each other to separate circuit connections therewith, yet operable upon association of a cord plug socket therewith for both of the circuit connections to be made with the one socket.

Still another object is to provide a cover member for each of the pairs of prongs and means to positively insure that one cover member will be closed when the other one is opened for permitting connection of a cord plug therewith thereby eliminating any exposed live prongs.

With these and other objects in view, my invention consists in the construction, arrangement and combination of the various parts of my device whereby the objects contemplated are attained, as hereinafter more fully set forth, pointed out in my claims and illustrated in the accompanying drawing, in which:

Figure 1 is a plan view of a sadiron showing my electric circuit and plug connections embodied therein.

Figure 2 is a sectional view on the line 2—2 of Figure 1 showing the parts on a reduced scale and showing the terminal prongs and the housing therefor in rear elevation.

Figure 3 is an enlarged sectional view on the line 3—3 of Figure 2 showing the prongs in greater detail.

Figure 4 is a sectional view on the line 4—4 of Figure 3 showing a cord plug associated with one set of terminals.

Figure 5 is a sectional view on the line 5—5 of Figure 3.

Figure 6 is a plan view of a portion of Figure 1 showing the cord plug associated with another set of terminals on a reduced scale; and

Figure 7 is an electrodiagrammatic view showing the circuit connections and a plug associated with one set of the terminals.

On the accompanying drawing I have used the reference numeral 10 to indicate a sole plate and 12 a cover therefor. A handle for the sadiron is indicated at 13 in Figure 1 and the central part thereof is broken away to show a housing 14.

15 The housing 14 has a pair of openings 15 and 16 adapted to be normally closed by cover members 17 and 18, respectively. The cover members 17 and 18 are hinged as at 19 to the housing 14.

The housing 14 encloses two sets of terminals, one of which comprises prongs P and the other comprises prongs P'. The prongs P and one of the prongs P' are indicated as 19, 20 and 21, respectively. They are of the usual construction for cooperation with the usual split socket members 22 of a cord plug 23 and are supported by flanges 24 extending upwardly from the cover plate 12. The prongs are suitably insulated with relation to the flanges 24 in the usual manner.

The other prong F', however, is of compound character comprising two prong elements 25 and 26. The elements 25 and 26 have prong portions 25^a and 26^a, which are semi-tubular or semi-cylindrical in shape. Between them a strip of insulation 27 is provided so that they are electrically insulated from each other.

30 In the sole plate 10 a heating element H is provided and this element has end terminals 29 and 30 and a central terminal 32. This divides the heating element into two parts which may 35 be connected in series or parallel with each other as will hereinafter appear.

Wires 33 and 34 connect the end terminal 29 with the terminal prongs 26 and 19. Wires 34 and 35 connect the other end terminal 30 with the prongs 25 and 20. A wire 36 connects the center terminal 32 with the prong 21.

40 From the construction of the parts thus far described it will be obvious that when the split socket members 22 of a standard cord plug 23 are 45 associated with the prongs P' as in Figures 1, 4 and 7, the prongs 25 and 26 will be electrically connected together by one of the socket members and that socket member will be connected with the terminals 29 and 30 of the heating element 55 H. The remaining terminal 32 will be connected

with the other socket member 22 and thus the two parts of the heating element are connected in parallel with each other.

When the cord plug 23 is removed from the prongs P' and associated with the prongs P as in Figure 6 then the two parts of the heating element H will be connected in series. Thus I am able with the use of two sets of prongs, one set of which includes a compound prong of the character disclosed, to use a standard cord plug for either parallel or series connection of the two parts of the heating element H together.

Inasmuch as all of the prongs P and P' are alive when the cord plug 23 is associated with either pair of them it is desirable to have the cover 17 or 18 for the other pair closed to prevent any one from inserting his finger to a position that would contact with the unused prongs.

I therefore provide the covers 17 and 18 and also provide a control member 37 therefor consisting of a plate pivoted at 38 to the housing 14. This plate may be swung to overlie the cover 17 as in Figure 4 to retain it positively closed when the cover 18 is opened, and vice versa.

My circuit and plug connections can be used either in connection with two different voltages or in connection with one voltage where it is desired to have two different heats from the same heating element.

For this purpose I have applied two sets of indicia to the housing 14, one of which is provided for two voltages. The word "Volts" has a pair of arrows extending therefrom indicating "110" and "220." When the control element 37 is in the position of Figure 6 it covers "110" and thereby exposes "220" to indicate that the plug 23 associated with the terminals P under the cover 17 makes the proper connections for 220 volt operation.

When the control element 37 is swung to its other position, then the plug may be associated with the prongs P' or 110 volt operation and "110" will be uncovered.

When 110 volts only is used, high or low heat can be secured from the heating element H. The indicia applicable for this purpose is indicated in Figure 6 as follows: "110 volts," "Hi-heat" and "Lo-heat." Here again the control plate 37 covers one indicia when the other is applicable.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

I claim as my invention:

1. In an electrical appliance, a heating element, two pairs of terminal prongs, one pair being effective to connect the two halves of said heating element in series circuit with a cord plug when associated therewith and the other

pair thereof being effective to connect the two halves of the heating element in parallel circuit with the cord plug when associated therewith, a housing for said pairs of prongs, a cover for each pair of prongs, a shiftable control element operable to positively retain one of said covers closed while the other one is permitted to open and vice versa, and indicia on said housing, a part of said indicia being concealed by said control element when the control element is in position to retain one of said covers closed, and another part of said indicia being concealed by said control element when in position to retain the other one of said covers closed.

2. In a structure of the character described, an electrical appliance having a heating element, end terminals and a central terminal therefor and two pairs of terminal prongs for said heating element, one pair of said prongs being connected with the end terminals of said heating element and the other pair comprising a single prong and a compound prong, said single prong being connected with said central terminal and said compound prong comprising a pair of semicylindrical prong elements insulated from each other and associated with each other to provide a compound prong of substantially the same size as the single prong, said prong elements being connected, each with one of said end terminals whereby association of a standard cord plug with one pair of prongs will connect the two halves of said heating element in series circuit with the cord plug and association of said cord plug with the other pair of prongs will connect the two halves of the heating element in parallel circuit with the cord plug, a housing for said pair of prongs, a cover for each pair of prongs and a shiftable control element operable to positively retain either of said covers closed while the other one is permitted to open for associating the cord with the terminals normally covered thereby.

3. In an electric iron, a housing member, a pair of openings through the wall of said housing member, electrical terminals within each of said openings, a hinged cover for each opening, and a locking plate pivoted on said housing, said plate being engageable with either of said covers to maintain the cover positively in closed position, said plate being of such dimensions that when it is swung about its pivot sufficiently to release one cover, it simultaneously engages the other cover to maintain the latter closed.

4. In an electric iron, a housing member, a handle extending longitudinally thereof, a pair of openings through the wall of said housing, one on each side of said handle, electrical terminals within each of said openings, a cover for each of said openings, and a shiftable control element operable to positively retain one of said covers closed while the other one is permitted to open and vice versa.

GWILYM STANLEY BRAUN.
